UNITED STATES PATENT OFFICE.

JARED MARIS, OF COLUMBUS, OHIO.

DESIGN FOR THE ORNAMENTATION OF WHEEL-HUBS.

SPECIFICATION forming part of Design No. 16,295, dated September 29, 1885.

Application filed June 23, 1885. Term of patent 3½ years.

To all whom it may concern:

Be it known that I, JARED MARIS, a citizen of the United States, residing at Columbus, in the county of Franklin and State of Ohio, have 5 invented and produced a new and original Design for Wheel-Hubs, of which the following is a specification, reference being had to the accompanying drawings, forming part thereof.

My invention relates to a design for the ornamentation of wheel-hubs; and it consists in scallops on the periphery of one or both flanges of the hub and pointed projections between the scallops.

In the accompanying drawings, Figure 1 is 15 a view in side elevation showing the scallops A and projections A' on the periphery of one flange. Fig. 2 is a plan view of the same, and Fig. 3 is a plan view showing the scallops and projections on both flanges.

20 The projections A' can be diamond shape—that is, they can start from the bases of the scallops and project out on a line with the

outer edges of the scallops, as shown in Figs. 1, 2, and 3—or they can be of V shape, as shown in Fig. 4. The size of the scallops A 25 and projections A' can be varied at pleasure.

Having fully described my design, what I claim as new, and desire to secure by Letters Patent, is—

1. In a design for a hub, the ornamentation 30 of the same, consisting in scallops on the periphery of one flange of the hub and projections located between the scallops, as shown and described.

2. In a design for a wheel-hub, the ornamentation of the same, consisting in scallops on the peripheries of both flanges and pointed 35 projections located between the scallops, as shown and described.

JARED MARIS.
